UNITED STATES PATENT OFFICE.

SAMUEL M. JACKSON JACOBS, OF NEW YORK, N. Y.

CAP FOR CIGARS.

1,294,107.

Specification of Letters Patent. Patented Feb. 11, 1919.

Application filed January 20, 1917. Serial No. 143,432.

To all whom it may concern:

Be it known that I, SAMUEL M. JACKSON JACOBS, a citizen of the United States, and a resident of the borough of Manhattan, 5 city of New York, county and State of New York, have made certain new and useful Inventions in Caps for Cigars, of which the following is a specification.

The invention relates to caps or the like for cigars. According to my invention there is applied to the "tuck" or lighting end of the cigar a member for protecting the cigar. This is accomplished by providing at the tuck or lighting end of the cigar a cap or 5 the like which will serve to protect said end from fracture. The protecting member is made in the form of a closed removable cap—the preferred form—and it serves to protect the tuck or lighting end of the cigar 0 from dust or foreign matter which might otherwise settle and accumulate on the cigar or within the interstices at the end of the cigar and remain as a contaminating agent. A cap on the end of a cigar also tends to 5 maintain a uniform degree of moisture within the cigar.

As showing certain specific embodiments of the invention reference is made to the drawings forming a part of this specification, in which drawings—

Figure 1 is a perspective view of a cigar having a lighting end with a cap applied thereto.

Fig. 2 is a sectional view of a cigar taken as on the plane indicated by line 2—2 of Fig. 1 looking in the direction of the arrows.

Fig. 3 is a perspective view of an open box filled with cigars—cigars for instance of the type shown in Fig. 1.

A cigar with an open tuck or full open lighting end is indicated by 1 and the lighting end thereof is protected by a cap 2 which cap comprises material such as tinfoil 3 that is a thin sheet material bent into cap formation and held in place by a band 4, preferably of paper, which band is herein referred to as a retaining band. From an inspection of the drawings and from what has preceded it will be clear that the tinfoil portion 3 constitutes a covering formed of thin sheet material bent or folded in place so as to fit the end of the cigar and so that the covering thus made comprises a tip or tip portion and a lateral portion the latter of which surrounds and extends along the

end portion 1 of the cigar. From the drawings it will also be seen that the retaining band 4 extends the full length of the lateral portion. This band 4 is preferably utilized as the label carrying band and bears such 60 marks as the trademark or advertising legend of the maker, and can also be employed as a means to properly dress the cigar. It will be manifest that the cap shown in Fig. 2 can be readily removed without any likelihood of rupturing the wrapper of the cigar, thus avoiding an objectionable feature which is frequently encountered when removing the band which heretofore has been usually placed about the center of a cigar. 70

This band serves the function of strengthening the cigar at the lighting end, for instance, against rupture when the cigar is carried in the pocket. The protecting member is in the form of a removable cap, as 75 shown, and dust and foreign matter cannot accumulate on the lighting end of the cigar, thus preventing any source of contamination at this place.

The projection or tab designated by 7^a 80 can be gripped between the thumb and finger to facilitate the removal of the cigar from the box and also the subsequent removal of the band from the cigar.

It will be noted that the cigars are arranged in the box in such a manner that the projecting portion or tab 7^a are uppermost to facilitate the removal of a cigar and particularly the removal of the first cigar from its layer. 85

In this specification the word "cigar" is to be broadly construed so as to cover any other form of article to be smoked such, for instance, as cigarettes, cheroots, stogies and the like, as well as what is usually known in 90 the trade as a cigar.

The invention may be embodied in various forms and modifications without departing from the spirit and scope of the invention. 100

What I claim and desire to secure by Letters Patent of the United States is:

1. A cigar having at the tuck or lighting end thereof a covering of tinfoil bent or folded in place so as to cover and fit the end portion of the cigar and which covering when in place provides a tip portion and a lateral portion the latter of which surrounds the end portion of the cigar, and a retaining band of paper that surrounds the said lat- 105

110

eral portion, that extends the full length of the lateral portion, and that serves to hold said covering in place.

2. A cigar having at the tuck or lighting end thereof a covering of thin sheet material bent or folded in place so as to cover, fit and surround the end portion of the cigar, and a retaining band of paper that surrounds said covering and serves to retain
- 5 the covering in place, said band being provided with a projection or tab which can be seized or gripped between the fingers so as to facilitate the removal of the cigar from a layer of cigars.
- 10 3. A cigar with an open tuck or cut lighting end and having at said end a cap which
- 15

includes a piece of thin sheet material that provides a tip covering the cut end of the cigar and which sheet material is also bent or folded so as to form a lateral portion 20 surrounding the end portion of the cigar and a retaining band that surrounds said lateral portion of the thin material and that extends the full length of said lateral portion.

25

This specification signed and witnessed this 16th day of January, A. D. 1917.
